UNITED STATES PATENT OFFICE.

GEORGE WASHINGTON EMMONS, OF ONTARIO, WISCONSIN.

ERASER-CLEANING APPARATUS.

Application filed October 21, 1921. Serial No. 509,378.

To all whom it may concern:

Be it known that I, GEORGE WASHINGTON EMMONS, a citizen of the United States, residing at Ontario, in the county of Vernon 5 and State of Wisconsin, have invented certain new and useful Improvements in an Eraser-Cleaning Apparatus; and I do hereby declare the following to be a full, clear, and exact description of the invention, such as will enable others skilled in the art to which it appertains to make and use the same.

The object of the invention is to provide an apparatus for use in connection with the cleaning or removal of chalk dust from black board erasers and the like and which under ordinary circumstances are cleaned simply by striking the face of the eraser upon a flat object or clapping two erasers 20 together, one being held in each hand with the disadvantage that the flying dust fills the air to the discomfort of the operator and everyone in the vicinity of the operation and the dust collects on surrounding objects with 25 resultant annoyance; and more particularly the object is to provide a holder or frame in which a plurality of erasers may be placed as they become filled with chalk dust and in which they may be secured in proper 30 position to be cleaned in one operation either by means of a broom or a suction cleaning apparatus, the rack serving as a dispensing means from which the cleaned erasers may subsequently be withdrawn one 35 at the time as they are required for use and which may be suspended in a convenient position in the school or class room with the erasers readily accessible to the pupils; and with these objects in view the invention 40 consists in a construction, combination and relation of parts of which a preferred embodiment is illustrated in the drawings, wherein:

Figure 1 is a view in front elevation of 45 the cleaning apparatus, parts of the apparatus being broken away for the purpose of clearness.

Figure 2 is a sectional view taken on the plane indicated by the line 2-2 of Figure 6.

Figure 3 is a view in front elevation of the lower portion of the base of the apparatus.

Figure 4 is a sectional view taken on a plane extending centrally and longitudinally 55 through the apparatus.

Figures 5 and 6 are edge views of the apparatus showing the clamping means respectively in closed and open position.

Figure 7 is a detail view of one of the links of the clamping frame. 60

Figure 8 is a detail view of one of the side bars of the slide frame, and

Figure 9 is a sectional view on an enlarged scale taken on the plane indicated by the line 9-9 of Figure 6. 65

The apparatus consists essentially of two relatively slidable members represented in the construction illustrated as a base 10 and a guide frame 11, the latter consisting of side bars connected at their upper ends by a round or handle 12 and side bars of the frame 11, being mounted upon the side edges of the base member 10 by means of slots 13 in the frame 11 engaging headed guide pins 14 on the base member 10; and a clamping frame mounted for swinging movement with relation to the relatively slidable members 10 and 11 and consisting essentially of the side bars 15 connected by transverse bearing bars 16 and connected with the base by means of links 17. 70

The relatively slidable base and frame members carrying a plurality of holder bars of which the lowermost bar 18 is secured by screws 18^a or like fastening means to the base member at its lower edge, the uppermost bar 19 is carried by the frame member by having the reduced terminals 19^a thereof fitted in openings 19^b in the side bars of the frame member and secured by set screws 19^c, 75 while the intermediate holding bars 20, of which any desired number may be employed are movable relatively to both the base member and the frame member, longitudinally thereof, the reduced extremities 20^a thereof being fitted in elongated openings or slots 20^b in the side bars of the frame member. 80

These holder bars are undercut at their upper and lower edges to form bevels 21 for engagement with the end edges of the backs 22 of the black board erasers E, so that when the backs of the erasers are disposed upon the surface of the base member and the holder bars are relatively adjusted to bear against the said eraser backs, the latter are clamped rigidly in the rack so that a broom or pneumatic cleaner may readily be used to 85 remove the dust from the fibre portions thereof. This adjustment of the holder bars 90 is effected by a relatively longitudinal move-

100

110

ment of the base and frame members of the rack, the base member either being moved upwardly in the frame member or the frame member downwardly with relation to the base member, so as to force the terminal holder members 18 and 19 toward each other. The intermediate loose members 20 are adapted to accomodate themselves to the length of the erasers interposed therebetween as openings or slots 19^b are shorter than those at 20^b so that an effective clamping of all of the erasers may be effected in a single operation.

The links 17 of the clamping frame are provided with openings 22^a for engagement with pins or studs 23 projecting from the side bars of the slide frame member 11 and with longitudinally elongated openings or slots 24 for engagement with the headed studs 14, and consequently while the clamping frame in the open position of the rack stands outward from the plane of the main members consisting of the base and slide frame as indicated in Figure 2 so that the transverse bars 16 form rests to receive the erasers with the lower edges of their backs bearing upon the holder bars 20, the movement of the side bars of the clamp frame rearwardly toward the plane of the base causes the relative sliding movement of the base and slide frame members and also the folding of the erasers into their proper position for engagement by the holder bars 18, 19 and 20, and when the clamp frame has reached a position parallel with the main members, the latter may be locked in their eraser clamping relations by latches 25 pivoted as at 26 upon the slide frame side members and provided with studs 27 for selective engagement with seats 28 of which a series is arranged at each side edge of the base member near its upper end. The base member is also preferably provided with a hand hold 29 at its upper end which serves as a hanger for engagement with a nail or hook by which the rack may be suspended on the wall within convenient reach of the pupils so that with the rack in the open position the erasers may readily be withdrawn successively as required or may be replaced therein as they become filled with dust and require cleaning.

It is the usual practice after each day's school session for the janitor or other authorized person to remove the erasers for the purpose of cleaning them preparatory to the next day's session and with the apparatus described it is only necessary for the operator to close the rack to clamp and lock the erasers therein and then carry the same to a convenient place where a broom or pneumatic cleaner may be employed, the surfaces of all of the fiber members of the erasers being in a common plane to facilitate the cleaning operation.

As a further convenience the lower end of the base member may be provided with lugs or feet 30 adapted to be rested upon the floor or a table or other like support.

In clamping or releasing the erasers, the base 10 may be held against movement by grasping the hand hold 29 in one hand and the guide frame 11 moved with respect to the base 10 through the medium of the handle 12 grasped in the other hand. One way of manipulating the apparatus to effect a release of the erasers after they have been cleaned, is to first swing the latches 25 out of the notches 28, and thence, while holding the base 10 against movement through the medium of the hand hold 29, move the guide frame 11 upwardly with respect thereto through the medium of the handle 12. This manipulation of the guide frame 11 with respect to the base 10 moves the holder bars 19 and 20 vertically or into spread relation and moves the bars 16 outwardly and away from the holder bars 19 and 20 to a position where links 17 are substantially horizontal. The erasers are thus released but will tilt forwardly and downwardly resting against bar 16 and with their lower ends still in engagement with the holder bars 19 and 20, from which position, they may be individually removed as occasion requires.

While the preferred embodiment of this invention is shown and described it will be understood that minor changes in the details of construction and arrangement of parts may be resorted to within the scope of what is claimed without departing from the spirit of the invention.

Having thus described the invention, what I claim is:

1. An eraser holding and cleaning rack having relatively slidable base and frame members and transverse holder bars between which the erasers may be arranged, the terminal bars being carried respectively by said members and the intermediate bars being loose for movement to suit the length of the interposed eraser.

2. An eraser holding and cleaning rack having relatively slidable base and frame members and transverse holder bars between which the erasers may be arranged, the terminal bars being carried respectively by said members and the intermediate bars being loose for movement to suit the length of the interposed eraser, the spacing edges of the holder bars being under cut for engagement with the end edges of the eraser backs.

3. An eraser holding and cleaning rack having relatively slidable base and frame members and transverse holder bars between which the erasers may be arranged, the terminal bars being carried respectively by said members and the intermediate bars being loose for movement to suit the length of the interposed eraser, and the latch mechanism

- for securing said members in their eraser clamping relation.
4. An eraser holding and cleaning rack having relatively slidable base and frame members and transverse holder bars between which the erasers may be arranged, the terminal bars being carried respectively by said members and the intermediate bars being loose for movement to suit the length of the 10 interposed eraser, and latch mechanism for securing said members in their eraser clamping relation, and consisting of latch members pivoted upon the frame members for engagement with seats on the base member.
- 15 5. An eraser holding and cleaning rack having relatively slidable base and frame members and transverse holder bars between which the erasers may be arranged, the terminal bars being carried respectively said 20 members and the intermediate bars being loose for movement to suit the length of the interposed eraser, and a swinging clamp member having cross bars movable toward and from the plane of said relatively slid- 25 able members for supporting the erasers in inclined relation with the base member.
6. An eraser holding and cleaning rack having relatively slidable base and frame members and transverse holder bars between 30 which the erasers may be arranged, the terminal bars being carried respectively by said members and the intermediate bars being loose for movement to suit the length of the interposed eraser, and a swinging clamp 35 member having side bars connected by trans- verse rest bars movable toward and from
- the plane of the base member and links connecting said side bars with the base member.
7. An eraser holding and cleaning rack having relatively slidable base and frame 40 members and transverse holder bars between which the erasers may be arranged, the terminal bars being carried respectively by said members and the intermediate bars being loose for movement to suit the length of the 45 interposed eraser, and a clamp member having side bars connected by transverse rest bars and links carrying the side bars, pivot- ally mounted upon the side edges of the base member and connected with the side bars of 50 the frame member for effecting relative slid- ing movement of the base and frame mem- bers.
8. An eraser holding and cleaning rack having relatively slidable base and frame 55 members and transverse holder bars between which the erasers may be arranged, the terminal bars being carried respectively by said members and the intermediate bars being loose for movement to suit the length of the 60 interposed eraser, and a swinging clamp member having side bars connected by trans- verse rest bars and links having pivotal connec- tions respectively with the base and frame 65 members.

In testimony whereof I affix my signature in presence of two witnesses.

GEORGE WASHINGTON EMMONS.
